UNITED STATES PATENT OFFICE.

EDWIN H. PEASE, OF RACINE, WISCONSIN.

FANNING-MILL.

SPECIFICATION forming part of Letters Patent No. 312,157, dated February 10, 1885.

Application filed November 12, 1884. (No model.)

To all whom it may concern:

Be it known that I, EDWIN H. PEASE, a citizen of the United States, residing at Racine, in the county of Racine and State of Wisconsin, have invented certain new and useful Improvements in Fanning-Mills; and I do hereby declare the following to be a full, clear, and exact description of the invention, such as will enable others skilled in the art to which it appertains to make and use the same.

My invention relates to the style of fanning-mills organized in such a manner as to effect a preliminary separation of the dust and chaff from the wheat before it is subjected to the riddles and the usual fan-blast.

The object of my invention is to furnish a fanning-mill in which this preliminary separation of the dust and chaff is effected solely by the action of a suction-fan.

To this end my improvement consists of certain combinations, which are specifically pointed out in the claims, and the embodiment of which I will proceed to set forth in the ensuing detailed description.

Figure 1 is a side elevation of a fanning-mill embodying my improvement. Fig. 2 is a vertical longitudinal section of the same. Fig. 3 is a plan view of the same, the feed-slide of the hopper being omitted to show the dust-trunk. Fig. 4 is a perspective view of portions of the fanning-mill, illustrating more particularly the dust-trunk.

The same letters of reference indicate identical parts in all the figures.

The side boards A of the fanning-mill are constructed at the front end with the usual casing, A', which contains the blast-fan B. The end shaking-shoe, composed of the side boards D and screens or riddles C, is supported at each side by a pair of springs, E E', the lower ends of the springs being secured to the side boards A and the upper ends to the side boards D of the shoe. The shoe is reciprocated endwise by a pair of eccentrics, F F', and the eccentric-rods I' I'', the eccentrics being secured to the shaft B' of the blast-fan B. An inclined cross-board, D', of the shoe forms the bottom of the hopper G, constructed with the ordinary slide, G', for regulating the feed.

The construction of the fanning-mill described so far does not differ substantially from

other known fanning-mills. With these parts I combine a suction-fan, H, the case H' of which is mounted above the casing A' of the blast-fan B, and is provided with an air-port, h, at each side. The air-ports h open into the dust-trunk I, a flat chamber, which extends from the suction-fan to the front end of the shoe, reaching to a point above the cross-board d of the shoe, as clearly shown in Figs. 2 and 4. The dust-trunk I is made flaring, as shown, so that its mouth is about as wide as the riddles. A deflector, i, is erected on the dust-trunk just in front of the shoe, so that the grain falling from the hopper-bottom may find no lodgment on top of the dust-trunk, but be caused to fall to the riddles below the mouth of said trunk. As the grain passes the mouth of the dust-trunk it is subjected to a strong draft, 70 by which the dust and chaff mingled with the grain are separated therefrom and drawn into the suction-fan, from which they are discharged through the discharge-spout h'. The draft of the fan may be somewhat tempered by a valve, K, suspended over the riddles in front of the mouth of the dust-trunk I, the stem of the valve being combined with a ratchet and pawl, K', for the purpose of adjusting it. The draft-ports h of the suction-fan are provided with slides or valves h'', so that they can be opened more or less to govern the drafts.

I am aware that fanning-mills are known in which a preliminary separation of dust and chaff is effected, and in which even a suction-fan is used to aid in the separation, as shown in United States Patent No. 267,699.

I am also aware that fanning-mills are known in which the grain falling from the hopper is subjected to a draft created by the same suction-fan that acts supplementary to the riddles in the final separation.

I am also aware that an independent suction-fan has been combined with riddles and a blast-fan to create a strong current through a portion of the riddles and take off the chaff and light material.

My invention is distinguished from these known structures or combinations by the relative arrangement of the parts, as set forth in the claims, whereby superior results are obtained.

I claim as my invention—
1. The combination, substantially as before

set forth, of the hopper, the shaking sieves or riddles below the hopper, the blast-fan, the independent suction-fan, the suction or dust-trunk, which is arranged, substantially as described, so that the grain falling from the hopper-bottom to the riddles passes across the mouth of said trunk, and is there subjected to a cross-draft, and the deflector on the dust-trunk in front of the riddles.

10 2. The combination, substantially as before set forth, of the hopper, the shaking sieves or riddles below the hopper, the blast-fan, and the independent suction-fan, with the dust-

trunk having the deflector *i* in front of the riddles, and having its mouth reaching to and communicating with the space directly between the hopper-bottom and the riddles, a valve, *K*, suspended over the riddles and in front of the mouth of the dust-trunk, and suitable means for adjusting the valve. 15 20

In testimony whereof I affix my signature in presence of two witnesses.

EDWIN H. PEASE.
